UNITED STATES PATENT OFFICE.

LAWRENCE E. MAY, OF NASHVILLE, TENNESSEE.

PUMP.

1,401,094.

Specification of Letters Patent. Patented Dec. 20, 1921.

Application filed February 14, 1921. Serial No. 445,037.

To all whom it may concern:

Be it known that I, LAWRENCE E. MAY, a citizen of the United States, residing at Nashville, in the county of Davidson and State of Tennessee, have invented new and useful Improvements in Pumps, of which the following is a specification.

This invention relates to pumps, and has for its chief object the provision of a pump 10 by means of which heavy grease or oil can be conveniently dispensed from suitable containers, the invention being primarily intended for use in filling automobile transmission and differential casings.

15 The nature and advantages of the invention will be better understood when the following detail description is read in connection with the accompanying drawing, the invention residing in the combination, construction and arrangement of parts as claimed.

In the drawing forming part of this application, like numerals of reference indicate similar parts in the several views and wherein:

26 wherein:— Figure 1 is a vertical sectional view through the pump forming the subject matter of my invention.

Fig. 2 is a sectional view taken on line 2-2 of Fig. 1.

Referring to the drawing in detail, 10 indicates the tank or other suitable container, which may be stationary or mounted on wheels 11 so that it can be conveniently moved from place to place. Supported upon the top of the tank 10 and secured thereto in any suitable manner is a casting 11 having spaced parallel bores or openings of different diameters to slidably receive the pump cylinder 12 and outlet pipe 13 of the pump structure, said cylinder and pipe being arranged in parallelism and adapted to enter the tank 10 through the openings in the top thereof. This pump structure is sus-

45 ceptible of adjustment through said openings and may be properly positioned with relation to the tank and subsequently held in its adjusted position through the instrumentality of set screws or the like 14.

50. The lower end of the cylinder is threaded into a valve casing 15 which is slightly larger in diameter than the diameter of the cylinder 12, the casing having associated therewith an inwardly opening flap valve 16. The casing 15 being larger than the

55 16. The casing 15 being larger than the cylinder 12 allows heavy grease and oils to

readily enter the cylinder, and subsequently forced therefrom through the outlet pipe 13. A valve casing 15 communicates with a lateral offset branch 17 through which the lower end of the outlet pipe 13 is suitably coupled, a flap valve 17 being interposed between the coupling 18 and the branch 17 of the valve casing. The outlet pipe 13 is smaller in diameter than the diameter of the cylinder 12, while both the cylinder 10 and the outlet pipe 13 are of sufficient length to provide for the delivery of a predetermined quantity of grease or oil with each stroke of the piston 19. The piston reciprocates within the cylinder 12 and has associated therewith a rack bar 20, the latter sliding through a substantially L-shaped bracket 21 which has one end secured to the outlet pipe 13, and its opposite end secured to the casting 11. Journaled on this bracket 21 is a crank handle 22 which has associated therewith a gear 23, the latter meshing with the rack bar 20 so that when the crank is turned a reciprocatory motion is transmitted and imparted to the piston 19. A flexible discharge tube 24 is suitably coupled to the upper end of the outlet pipe 13, this tube having associated with its opposite end a nozzle 25.

The invention is very simple in construction and can be manipulated in a very easy manner to dispense heavy grease and oil, and is particularly useful in filling transmission and differential casings of automobiles, although its general application is contemplated by the claim. 90

While it is believed that from the foregoing description the nature and advantages of the invention will be readily apparent, I desire to have it understood that I do not limit myself to what is herein shown and described, and that such changes may be resorted to when desired, as fall within the scope of what is claimed. 95 10

What I claim is:—

In combination, a tank having an opening in the top thereof, a plate closing the opening and having spaced bores, a cylinder passed through one of the bores and arranged within the tank, a vertical offset portion formed on the lower end of the cylinder, an outlet pipe rising from the offset portion and passing through the other bore of said plate, a valve in the lower end of the cylinder, a second valve in said offset portions, a piston arranged to reciprocate

within the cylinder, a rack bar associated with the piston and projecting through the upper end of the cylinder, a bracket arranged exteriorly of the tank and supported by said plate, said bracket being associated with said outlet pipe, a crank handle journaled on said bracket, a gear associated with said crank and meshing with the rack bar to reciprocate the piston, means for limiting the movement of the rack bar in one direction, and a flexible tube coupled with one end of the outlet pipe.

In testimony whereof I affix my signature

LAWRENCE E. MAY
